CLAIM

We claim the ornamental design for a housing for latches and locks, as shown and described.

DESCRIPTION

Reference is made to the following concurrently filed design application of Lee S. Weinerman and Scott A. Arthurs wherein an identical housing is disclosed, namely Ser. No. 29/130,905. Reference also is made to the following concurrently filed design applications of Lee S. Weinerman and Scott A. Arthurs wherein housings having similarities to the housing of the present invention are disclosed, namely Ser. No. 29/130,902, Ser. No. 29/130,904, and Ser. No. 29/130,906.

FIG. 1 is a perspective view showing front portions of our new design;

FIG. 2 is a perspective view showing rear portions thereof;

FIG. 3 is a front side elevational view thereof;

FIG. 4 is a rear side elevational view thereof;

FIG. 5 is a bottom view thereof, it being understood that a top view would be a mirror image reversal of this view;

FIG. 6 is a left end view thereof; and,

FIG. 7 is a right end view thereof.
